UNITED STATES PATENT OFFICE.

CHARLES H. OHMART, OF WEST MILTON, OHIO.

FENCE-MACHINE.

SPECIFICATION forming part of Letters Patent No. 351,998, dated November 2, 1886.

Application filed June 1, 1886. Serial No. 203,798. (No model.)

To all whom it may concern:

Be it known that I, CHARLES H. OHMART, a citizen of the United States, and a resident of West Milton, in the county of Miami and State of Ohio, have invented certain new and useful Improvements in Fence-Machines; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of my improved fence-machine in its operative position, with portions of it broken away and shown in dotted line, and also with the tension-regulating device shown in a reversed position in relation to the rest of the machine. Fig. 2 is a perspective view taken from the other side, and showing the tension device in the opposite position. Fig. 3 is a vertical sectional view. Fig. 4 is a top plan view. Fig. 5 is a horizontal sectional view of one of the twister-heads, and Fig. 6 is a perspective detail view of one of the tension-regulating devices.

My invention relates to machines for building wire and picket fences in the place in 30 which they are to remain; and it consists in the improved construction and combination of parts, as will be hereinafter more fully set forth.

Referring to the accompanying drawings, in 35 which the same letters of reference indicate corresponding parts in all the figures, A A represent the top and bottom bars of the machine, the forward end of each of which is provided with the adjusting-holes B, and the rear 40 end with a stop or hook, C. The bars are kept parallel with each other and at a certain distance apart by means of the vertical end pieces, D D, and an upright, E, is secured to their intermediate portion by means of the 45 brackets F, one end of each of which is provided with an eye, G, which fits and slides upon the bar, while the other end is secured to the bar by means of a bolt which can be passed through one of the holes H, as desired. This 50 upright E is provided with a series of holes,

I, throughout its entire length, by means of which as many twister-head supports can be secured as it is desired to have strands of wire in the fence, and they can be secured at any distance apart as may be desirable. A stay 55 rod or brace, J, is bolted to the opposite ends of these supports by means of holes similar to those in the upright E. Each of these supports consists of two plates, K, having a central perforation, and a shank or handle, L, at 60 one side. Journaled in the perforations or bearings in each pair of these plates is a twister-head, which consists of a sprocket-wheel, M, having a hub or axle, N. On opposite sides of this hub are grooves or channels O, extending 65 its entire length, through which the wires pass and by means of which they are twisted between the pickets. A sprocket chain, P, passes over the top and bottom of these sprocket-wheels, and also engages with the intermediate 70 sprocket-wheels upon both sides, so that a positive motion is imparted to each of said wheels, and all the twister-heads are rotated in unison, when motion is imparted to one of them, preferably the top one, by means of a 75 bevel gear-wheel, Q, which is provided with two perforations, Q', which register with the grooves O, and with a square lug or axle, R, upon one side, which fits in a square hole in the hub N of the twister-head. This bevel-gear is operated by means of a bevel-pinion, S, having a crank or other driving mechanism at 80 the outer end of its shaft.

A pair of toggles, T, are secured at one end to the front ends of the bars A A and at the 85 other end to beaters U U, which slide upon the intermediate portions of the bars and are provided with a lip or lug, V, which bears against the picket when it is placed in position and holds it until the wires can be twisted 90 around it. These toggles are secured together by means of a bar, W, having a handle, X, adjustably secured to one side. After the picket has been secured in place by means of the twists in the strands of 95 wire, two levers, Y, which are pivotally secured in slots in the rear end piece and connected by a rod, Z, are operated by a handle on one of them, which causes the opposite ends of the levers to press against the roc

picket, which bears against the hooks or stops C and releases the same. When the picket has been released from the hooks C, the machine is drawn forward by means of a handle, A', the 5 upper end of which is slotted, which is secured to the lower end of the upright E and to the forward end piece, until the hooks C engage with the next picket, the ends of the levers Y in the meantime having been withdrawn into 10 the slots in the end piece. The beaters U are then drawn forward on the bars by means of the toggles T, another picket is inserted between the wires and forced back as far as it will go by means of the beaters and toggles, 15 when the wires are again twisted and the hooks C again released by the levers Y, and so on until the fence is completed. The machine is kept from moving forward when pressure is applied to the toggles by the hooks 20 C, which engage with one of the pickets, as described, and the distance between the pickets is regulated by means of the adjusting-holes B and H in the bars A.

For the purpose of supporting the machine 25 in a vertical position upon hilly or uneven ground, the forward end piece is provided with an adjustable foot-piece, B', which, with the foot-piece C' on the lower end of the upright E, affords a sufficient support for the 30 machine.

The tension-regulating device consists of a flat board or post, D', which is secured to a stake or post driven in the ground by means of the hooks E'. Upon one side of this board, 35 preferably the opposite one to that shown in Fig. 1 of the drawings, are placed a series of plates, F', having an outwardly-projecting lug, G', at each corner, and two slots, H'. Each of these lugs has a perforation, through 40 two of which pass the wires, and through the others the bolts I', the outer ends of which are provided with adjusting nuts, and the inner ends are provided with hooks J', which move in the slots H'. In operation the strands of 45 wire from the spools are passed in pairs through the perforations in two of the lugs G' of each of these tension-plates. Each one of the hooks J' is then put over one of the wires and the nuts turned up until the wires are 50 drawn out of a straight line to give the desired amount of friction as the wires pass from the spools to the machine where it is being twisted around or between the pickets.

The tension device can be placed at any distance in front of the machine, as the tension-plates prevent the wires from becoming entangled with each other, as well as regulating the tension to be given to them.

Having thus described my invention, I 60 claim—

1. In a fence-machine, the combination of a top and a bottom bar, end pieces secured thereto, a beater upon each of said bars, toggles secured to each of said beaters and to the forward ends of said bars, a pressure-bar connecting said toggles, a vertical series of revolving

7c
twister-heads secured to the intermediate portion of said top and bottom bars, and means for securing the rear end of said machine to the fence.

2. In a fence-machine, the combination of a top and a bottom bar, the rear end of each of which is provided with a hook or stop, end pieces, a beater on each of said bars, a vertical series of revolving twister-heads, and means 75 for disengaging said hooks or stops from the fence.

3. In a fence-machine, the combination of a top and a bottom bar, the rear end of each of which is provided with a hook or stop, end 80 pieces, the rear one of which is provided with slots, a lever in each of said slots, one of which is provided with a handle, a rod connecting said levers, beaters on said top and bottom bars, and a series of revolving twister- 85 heads.

4. In a fence-machine, the combination of a top and a bottom bar, each of which is provided with adjusting-holes at its front end and near its rear end, end pieces, a bracket having an 90 eye at one end, and means for securing the other end in said adjusting-holes near the rear of said bars, an upright secured to said brackets, twister-heads secured to said upright, toggles adjustably secured to the front ends of 95 said bars, beaters secured to said toggles, and means for securing the rear end of said machine to the fence.

5. In a fence-machine, the combination of a top and a bottom bar, end pieces, and an upright secured thereto, twister-head supports secured to said upright, a rod secured to the opposite ends of said supports, a revolving twister-head in each of said supports, beaters on said top and bottom bars, and means for 105 securing the rear end of said machine to the fence.

6. In a fence-machine, the combination of a frame consisting of a top and a bottom bar and end pieces, and an adjustable foot-piece secured 110 to one of said end pieces, said frame being provided with an upright carrying a series of twister-heads.

7. In a fence-machine, the combination of a frame, an upright having a vertical series of 115 twister-heads, and a handle, the forward or upper end of which is slotted, said handle being secured to said upright and to one end of said frame.

8. In a fence-machine, the combination of a 120 frame, an upright having a series of twister-head supports secured thereto, a twister-head in each of said supports, consisting of a sprocket-wheel with a hub or axle, said hub having longitudinal grooves in its sides and a 125 square hole in its center, a bevel gear-wheel having perforations registering with said grooves, and a square lug upon one side, and a beveled pinion engaging with said beveled gear-wheel.

9. A tension-regulating device for fence-machines, consisting of a post or board, a se- 130

ries of plates secured to one side, each of said plates having an outwardly-projecting lug at each of its corners, and two slots, and bolts in two of said lugs, having a hook on their 5 inner ends and an adjusting-nut on their outer ends.

In testimony that I claim the foregoing as

my own I have hereunto affixed my signature in presence of two witnesses.

CHARLES H. OHMART.
